GUM MASSAGING DEVICE

Jonah Salit, Brooklyn, N. Y.

Application January 16, 1939, Serial No. 251,107

19 Claims. (Cl. 128—62)

This invention relates to massaging devices and particularly to an improved gum massaging device, an object being to provide a construction wherein both sides of the gums may be massaged at the same time.

Another object of the invention is to provide an electrically actuated massaging device which may be readily adjusted by hand to cause the massaging heads to fit any thickness of gum of a person when in functioning position.

A further object of the invention is to provide a gum massaging device which is actuated by alternating current and which is provided with means for automatically causing the device to function when moved to a functioning position in the mouth.

An additional object, more specifically, is to provide an electrically actuated massaging device for gums wherein means are provided for varying the space between the massaging heads while the machine is in operation.

In the accompanying drawing—

Fig. 1 is a perspective view of a gum massaging device disclosing an embodiment of the invention, 25 an electric cord being shown plugged in functioning position;

Fig. 2 is a top plan view on an enlarged scale of the device shown in Fig. 1 with the upper part of the casing removed;

Fig. 3 is a longitudinal vertical sectional view through Fig. 2 approximately on the line 3—3;

Fig. 4 is a sectional view through Fig. 3 on the line 4—4;

Fig. 5 is a sectional view through Fig. 3 on the line 5—5;

Fig. 6 is a transverse sectional view through Fig. 3 on the line 6—6;

Fig. 7 is a detail fragmentary sectional view through Fig. 2 approximately on the line 7—7;

Fig. 8 is a fragmentary sectional view showing the detail mounting of one of the pivot members;

Fig. 9 is an enlarged fragmentary sectional view through Fig. 2 approximately on the line 9—9;

Fig. 10 is an elevation with certain parts in section, showing the means for transmitting motion from the vibrating armature to the solid heads, the same being a modified construction to that illustrated in Fig. 4; and

Fig. 11 is a side view of the structure shown in Fig. 10 looking at the same from the right, certain parts being broken away for better illustrating the construction.

Referring to the accompanying drawing by nu-

merals, 1 indicates a casing which is divided into two parts, namely, in what may be termed a top or cap 2 and a bottom 3. These members at the front are provided with arc-shaped cutaway portions 4 and 5 for accommodating the respective rock shafts 6 and 7. At the opposite end the casing is provided with an opening 8 (Fig. 3) in which the respective terminals 9 and 10 are positioned, said terminals being carried by a plate 11 preferably of insulating material. The lead-in wires 12 and 13 are secured to the inner ends of the terminals 9 and 10, as shown in Fig. 2, and these wires lead to the various parts hereinafter fully described.

Referring to the rock shafts 6 and 7, it will be observed that they extend almost through the casing 1 and at the rear or right hand end, as shown in Figs. 1 and 2, press against a metal plate 14 (Fig. 7). A cotter pin 15 (Fig. 6) extends through each of the rock shafts to prevent forward movement while the metal plate 14 prevents any rearward movement. The forward ends of the rock shafts are bent at 16 and 17 so as to be more or less arc-shaped, as illustrated particularly in Figs. 1, 4 and 5. As illustrated in Fig. 9, each of the arc-shaped ends 16 and 17 is provided with a reduced extension 18 and over this extension the shank 19 of the massaging head or applicator 20 is fitted. The massaging head 20 may be of any suitable material, as for instance rubber vulcanized to a desired hardness. The shank 19 is secured to the reduced extension 18 by a suitable screw 21. A covering consisting of a rubber tube 22 is provided for each of the rock shafts 6 and 7, said covering extending from a position overlapping the shank 19 to a position within the casing 1, as shown in Fig. 2. The rock shafts 6 and 7 are identical in construction except that they are made right and left, and in use normally lie open, as shown in Figs. 1 and 2. These rock shafts may be rocked so that the respective heads 20 may move toward each other even to a point where they will contact. By this arrangement the heads 20 may straddle the gum whether it is large or small.

After the device has been placed in position in the mouth so that the heads 20 will straddle the gum, member 23 is pushed inwardly toward the casing 1 and immediately the massaging heads will move toward each other and the vibration will take place whereby the heads 20 will tap or pummel the gums and thereby produce a massaging action. During the functioning of the heads 20, the device may be moved along the gums back and forth and also up and down so

that all parts of the gums may be treated. As the heads are preferably formed of rather firm vulcanized rubber, the gums will not be injured but may be properly exercised and in case the 5 heads should strike any of the teeth there will be no injury thereto.

In order to secure a proper vibration there is provided an armature 24. This armature is formed with a pair of ears 25 straddling the end 26 (Fig. 10 7) of a field magnet 27. It will be noted that the field magnet 27 is provided with ends 26 and 28 (Fig. 7) and also a central post 29 around which the coil 30 is fitted. When coil 30 is energized by alternating current from wires 12 and 15 13, it will quickly attract the armature 24 and then release the same whereupon a vibratory action is secured. This action is transmitted through the pivot bars 31 and 32 which are integral with or rigidly secured to the free end of 20 the armature 24. The pivot bars 31 and 32 coact with the link bars 33 and 34 (Fig. 4) for raising and lowering these bars. These link bars, adjacent the top and adjacent the bottom, are each provided with a cone-shaped depression 35 as 25 shown in Fig. 8 so that any of the journal members, as for instance the end of bar 31, may fit therein. It will be noted that the respective ends of the pivot pins 31 and 32 are tapering so that there may be a certain relative swinging movement 30 between the links 33 and 34 and the pivot pins 31 and 32 and also between the links and the rocking arms 36 and 37. These arms are preferably welded or otherwise rigidly secured to the rock shafts 6 and 7 at their highest point. 35 From Fig. 4 it will be observed that each link is provided with an indented section 38 and a tension bolt 39 extends through these indented sections so that a spring 40 may act on the nut 41 and on one of the indented portions 38 to 40 provide a desired tension between these parts so as to hold the links in proper functioning position and to adjust their tension in respect to arms 36 and 37 and the pivot bars 31 and 32.

By reason of the above outlined construction, 45 whenever the armature 24 moves up and down motion will be transmitted to the rock shafts 6 and 7 for rocking the same. The armature 24 is pivotally connected to the end post 26 through the ears 25 and through journal member 47. 50 Screw 42 is journalled in a post 44 rigidly secured by a screw or otherwise to a metal base 45 secured in the bottom 3 by screws 46 or by other suitable means. A similar post 44' is arranged on the opposite side, as shown in Fig. 6 and carries 55 the screw 43. A journal member 47 (Fig. 6) extends through the end post 26 and through the ears 25 of the armature 24 for swingably mounting the magnet and also the armature. A wearing plate 49, preferably of hardened steel, is arranged 60 against the end post 26 and is held in place by the screws 52 and 53 carried by the depending end 54 of armature 24. Member 47 is provided with an enlarged end 50, as shown in Fig. 6, which has a threaded recess receiving the 65 threaded end of screw 32. An internally threaded spacing sleeve 51 receives the threaded end of screw 43 and also the threaded end of the journal member 47. In this way the field magnet 27 is pivotally mounted. In order to adjust the 70 position of the armature 24 in respect to the end post 26 and also the end post 28, adjusting screws 52 and 53 have been provided. These pass through the depending end 54 of armature 24 and press against the wearing plate 49. After 75 adjusting the position of armature 24 in respect

to the magnet, the screws 52 and 53 will keep the armature firmly in position during the functioning of the device. Preferably the armature 24 is made from somewhat resilient material and, of course, is magnetic so as to be attracted when the field magnet 27 is energized. As the device is designed to use alternating current, whenever current is turned on to the coil 30 the armature 24 will be attracted and released rapidly so as to give intermittent downward pushes against 10 the outer ends of arms 36 and 37 and provide a desired vibration of the massaging heads 29. The resilient action of the armature will quickly return the armature to the position shown in Fig. 3 when the magnet, made up of the field 15 piece 27, posts 29, end posts 26 and 28 and coil 30, is deenergized. When the magnet is energized the armature 24 will move from the position shown in Fig. 3 downwardly a short distance and then be released so that it will quickly move 20 upwardly. If the current used is sixty cycles the movement will be at this rate. Over the front end post 28 of the magnet there is provided a U-shaped cover plate 55 of metal which is secured in place by a suitable bolt 56 extending entirely through post 28. A bracket 57 is formed either integral with or rigidly secured to the plate 55, and one end of a contractile spring 58 is looped thereover. The other end of spring 58 is looped over a hook 59 which may be secured to the base 45 or screwed directly into the bottom 3, as preferred.

The member or button 23 is provided with a shaft or pin 23' which slidably extends through suitable openings in the bottom 3 and base 45 so that when the button is moved pin 23' will push and swing the field piece 27 (Fig. 7) and associated parts until the heads 29 contact or come as near together as desired. An abutment, as for instance a cotter pin 60, extends through 40 pin 23' to limit its downward or outward movement.

A block of insulation 61 is connected with the post 28 by a screw or bolt 56 (Fig. 2) and this carries an electric switch composed principally 45 of two members, namely, plate 66 and spring member 62 which has a loop 63 as shown in Fig. 3. The loop 63 terminates in a contact end 64 that is adapted to press against the upturned contact end 65 of plate 66 which is arranged on 50 the opposite side of the block 61 to the plate or member 62. These two members are held in place by the respective screws 67 and 68. An abutment 69 of Bakelite, fiber, or other insulating material, has a portion embedded in the base 55 45 and a portion extending upwardly therefrom. The abutment 69 is positioned, as shown in Fig. 3, so that when the electric magnet and associated parts move toward base 45 under the action 60 of the spring 58, the contact end 64 of spring member 62 will be caused to leave the contact 65, or rather the contact 65 will move away from contact 64 and thereby break the circuit at this point. It is to be noted that the lead-in wire 62 leads to one terminal of the coil 30 and the lead-in wire 13 leads to the contact plate 66. An auxiliary wire 12' leads from the outlet end of coil 30 to the contact plate 62. It will, therefore, be seen that when the parts are in the position shown in Fig. 3, no current will flow even though the terminals 9 and 10 are connected to a suitable source of electrical supply, which must be alternating current. However, if the button or member 23 is pushed inwardly sufficiently to 70 75

move the magnet and cause the contact 65 to engage contact 64, current will flow and immediately the armature 24 will vibrate and move the links 33 and 34 back and forth and cause a rocking motion to take place in the rock shafts 6 and 7. This will cause the heads 20 to move toward and from each other very rapidly though only a short distance.

When the device is in use, the casing 1 is grasped by the hand and the heads 20 are placed in the mouth so as to straddle the gum, but during the placing of the device in the mouth and locating it at the desired point the finger of the operator does not push the member 23, but as soon as the device has been properly located in respect to the gum the member 23 is forced inwardly and the device will begin to function. The member 23 is forced inwardly until the heads 20 come in contact with the gums, whether the gums are thick or thin. Also by varying the pressure on the member 23 the pressure of the heads 20 against the gum will be varied though the vibration will be the same.

In Figs. 10 and 11 a slightly modified construction is shown wherein the link arrangement illustrated in Fig. 4 is modified. From Fig. 11 it will be seen that the combined members 70 and 71 equal the single link 33 shown in Fig. 4. The member 71 is provided with pressed portions similar to the portions 35 (Fig. 8) while the member 70 is provided with grooves 72 and 73, whereby the respective ends of the respective double pointed pins 74 and 75 may be properly pivotally mounted and a slight swinging and sliding movement allowed between these members and the member 70. It will be understood that the double pointed pins 74 are carried by the enlarged end 76 depending from the bar 31. The double pointed pin 75 is carried by the arm 36 (Fig. 10). A spring tension bolt 77 similar to bolt 39 is used for holding the members 70 and 71 in functioning position. The structure shown in Fig. 11 is to take the place of the bar 33, while a similar structure is provided to take the place of the bar 34 in this form of the invention. It will be understood that when the bars 33 and 34 are used the structure shown in Figs. 10 and 11 is of course not used. The structure shown in Figs. 10 and 50 11 may be substituted for the structure shown in Fig. 4 without changing any of the other parts except the arms 36 and 37 and the pivotal bars 31 and 32 as these members must conform to the structure shown in Fig. 11 to operate with 55 the members 70 and 71. The casing 1 may be Bakelite or other suitable material and preferably is made in two parts, namely, the top 2 and the bottom 3. Base 45 is preferably of metal and is rigidly secured by screws to bottom 3 and carries all of the moving parts of the device. Suitable screws 78 are preferably used for securing the top 2 to the bottom 3. These screws extend through the bottom 3 upwardly into the thickened portions of the top 2, whereby the top is 60 normally rigidly held in place but may be removed at any time when access to the interior is desired.

I claim:

1. A massaging device comprising a handle, a pair of shafts extending from said handle, each of said shafts having an outer end provided with a massaging head, electrically actuated means carried by said handle for vibrating said heads, and manually actuated means for turning on 70 said electrically actuated means, said manually

actuated means also moving said heads toward each other.

2. A massaging device including a handle, a pair of shafts, a massaging head carried by each of said shafts, and means for rocking said shafts on 5 their longitudinal axes for causing said heads to function.

3. A massaging device including a handle, a pair of shafts, a massaging head carried by each of said shafts, means for rocking said shafts on 10 their longitudinal axes for causing said heads to function, and electrically actuated means for causing said heads to vibrate.

4. A massaging device including a handle, a pair of members carrying massaging heads at 15 their outer ends, electrically actuated means for causing said heads to vibrate and means for moving said heads toward and from each other while they are being vibrated without changing the 20 length of vibration.

5. A massaging device including a handle, a pair of shafts extending therefrom, a massaging applicator carried by each of said shafts at the outer ends thereof and means including a manually operated sliding member for mechanically 25 actuating said shafts for varying the distance between said applicators.

6. A massaging device including a handle, a pair of shafts extending therefrom, a massaging applicator carried by each of said shafts at the 30 outer ends thereof, and means including a manually operated sliding member for mechanically actuating said shafts for varying the distance between said applicators and electrically operated means for vibrating said applicators. 35

7. A massaging device including a handle, a pair of members movable toward and from each other, a massaging head carried by each of said members, a spring tending to move said heads from each other, hand-actuated means for moving said heads toward each other, and electrically actuated means for causing said heads to vibrate as they are moved by said spring and the hand-actuated means. 40

8. A massaging device including a pair of 45 shafts, a massaging head carried by each of said shafts at the end thereof, swinging electrically actuated means for causing said heads to vibrate, means for moving said heads toward and from the plane in which said swinging electrically actuated means functions, and a handle carrying said shafts. 50

9. A massaging device including a pair of facing massaging heads, a shaft carrying each of said heads, an arm connected with each of said shafts, a link connected to each of said arms, an armature connected to said links, and an alternating current actuated magnet for causing said armature to vibrate. 55

10. A massaging device including a handle, a pair of shafts carried by said handle, a massaging head at the end of each of said shafts farthest from said handle, electrically actuated means for vibrating said shafts so that they will rock on their longitudinal axes, spring-actuated means for moving said shafts to separate said heads, and manually actuated means for moving said shafts for causing said heads to approach each other. 60

11. A massaging device including a pair of 70 facing massaging heads, a shaft carrying each of said heads, a vibrating engine, and means including a pair of articulate links for connecting the engine with the shafts so that vibration from the engine will be transmitted to the shafts and 75

will cause them to rock on their longitudinal axes.

12. A massaging device including a handle, a pair of shafts, a massaging applicator carried by each of said shafts and means for moving said applicators toward and from a plane passing centrally through said handle and between said shafts, the forward end of each of said shafts having a portion extending outwardly from said plane and a secondary portion extending from the first-mentioned portion at an angle thereto, the said portions of both of said shafts presenting generally a U-shaped structure.
13. A massaging device including a handle, a pair of shafts, a massaging applicator carried by each of said shafts, means for moving said applicators toward and from a plane passing centrally through said handle and between said shafts, the forward end of each of said shafts having a portion extending outwardly from said plane and a secondary portion extending from the first-mentioned portion at an angle thereto, the said portions of both of said shafts presenting generally a U-shaped structure, and electrically actuated means for causing said applicators to vibrate.

14. A massaging device including a pair of facing massaging heads, shafts for moving said heads toward and from each other, a spring actuating to move the shafts so that they will actuate said heads, a hand-actuated member for moving the shafts so that said heads will move toward each other, means for vibrating said heads, said means including a vibrating electric engine and a plurality of articulated members for connecting said engine with said shafts.

15. A massaging device comprising a pair of shafts having spaced ends, an arm rigidly secured to each of said shafts extending laterally from the shafts and a massaging head arranged on each of said ends, electrically actuated means for causing said ends to move toward and from each other at a high rate of speed, spring actuated means for swinging said arms simultaneously causing said shafts to be rocked on their longitudinal axes for moving said heads apart, and manually actuated means for moving said heads toward each other against the action of said spring means.

16. A massaging device including a pair of massaging heads, manually actuated means for moving said heads to and from each other, and means for vibrating said heads, said last mentioned means including an alternating current magnet, a resilient armature adapted to be

moved in one direction by the magnet and adapted to move itself by reason of its resiliency in the opposite direction, articulated means for connecting the free end of said armature with the means for moving said heads toward and from each other so as to give a vibratory action to said heads, and manually actuated means for opening the circuit of said magnet.

17. A massaging device including a pair of facing massaging heads, a rock shaft for each of said heads for causing the heads to move toward and from each other, and means for causing said rock shafts to vibrate, said means including an alternating current magnet, means for pivotally mounting said magnet, an armature pivotally mounted on the magnet, a pair of set screws for adjusting the position of the armature in respect to the magnet, a circuit for said magnet including a switch, and manually actuated means for simultaneously moving said switch to an open position and for rocking said rock shafts to move said heads toward each other.

18. A massaging device including a pair of facing massaging heads, a rock shaft for each of said heads, an arm rigidly secured to each of said rock shafts, a double-ended pivot pin carried by each of said arms, a resilient armature, a double-ended pin carried by the free end of said armature for each of said arms, a link structure for connecting the pivot pins of the arms with the pivot pins of the armature, said link structure including a pair of bars having depressions for receiving the combined ends of the respective pivot pins, a spring actuated bolt for holding the bars in functioning position and an alternating current magnet for actuating said armature.

19. A massaging device including a pair of facing massaging heads, a pair of rock shafts secured to the respective heads, an arm rigidly secured to each of said rock shafts, said arms having tapering outer ends, a resilient armature, a pair of pivotal arms having tapered outer ends carried by the other end of said armature, a link for each of said arms, each of said links having a pair of depressions, one depression receiving the tapered end of an arm and the other depression receiving the tapered end of a pivotal bar, resilient means for holding said links in functioning position, an alternating current magnet co-acting with said armature for causing the armature to function and lead-in wires for said magnet, said lead-in wires including a switch.
